UNITED STATES PATENT OFFICE

156,197

DESIGN FOR A WATCH BOX

George F. Brown, Cattaraugus, N. Y., assignor to
Plastic Engineering & Development Co., Salamanca, N. Y., a partnership

Application February 1, 1949, Serial No. 607

Term of patent 3½ years

(Cl. D80—5)

To all whom it may concern:

Be it known that I, George F. Brown, a citizen of the United States, residing at Cattaraugus, in the county of Cattaraugus and State of New York, have invented a new, original, and ornamental Design for a Watch Box, of which the following is a specification, reference being had to the accompanying drawing, forming part thereof.

Fig. 1 is a perspective view of a watch box, showing my new design with the cover in closed position;

Fig. 2 is a perspective view of the box with the cover in opened position;

Fig. 3 is an end view of the box with the cover in closed position; and

Fig. 4 is a vertical longitudinal sectional view, taken substantially on the line 4—4 of Fig. 1, and

shows the ornamentation on the interior front walls of the body and cover of the box.

I claim:

The ornamental design for a watch box, substantially as shown and described.

GEORGE F. BROWN.
